UNITED STATES PATENT OFFICE.

JAMES RANDOLPH COURTENAY GALE, OF SUTTON, ENGLAND.

APPARATUS FOR CONTROLLING THE WIND SUPPLY AND PRESSURE IN ORGANS.

SPECIFICATION forming part of Letters Patent No. 691,900, dated January 28, 1902.

Application filed May 11, 1901. Serial No. 59,722. (No model.)

To all whom it may concern:

Be it known that I, JAMES RANDOLPH COURTENAY GALE, clerk in Holy Orders, residing at Christ's Church Vicarage, Sutton, in 5 the county of Surrey, England, have invented certain Improved Apparatus for Controlling the Wind Supply and Pressure in Organs, Harmoniums, and Similar Instruments; and I do hereby declare the following to be a full, clear, 10 and exact description of the invention, such as will enable others skilled in the art to which it appertains to make and use the same.

My invention relates to improvements in apparatus for controlling the wind supply and 15 pressure in organs, harmoniums, and similar instruments, whereby the performer, notwithstanding the constant wind-pressure supplied to the trunk, is able to vary the wind-pressure in the wind-chest in or upon which the 20 reeds or pipes are planted, and thereby obtain a considerable range of expression. I attain this object by means of the mechanism illustrated in the accompanying drawings, in which like figures refer to similar parts in all 25 the views.

Figure 1 is a longitudinal part section. Fig. 2 is a longitudinal part section of a modification. Fig. 3 is a part-sectional side view of Fig. 1. Fig. 4 is a part-sectional side view 30 of Fig. 2. Fig. 5 is a longitudinal part section of a double pallet-valve.

1 represents the wind trunk or channel conveying wind at the highest pressure required from the feeder-reservoir or the like independent supply. At a suitable point in the 35 trunk, but preferably as near to the reeds or pipes as convenient, I insert a pierced diaphragm 2 and fit the same with a valve 3, pivoted, as at 4, and provided with leather-faced 40 flanges 5. This valve is connected by the stem 6, knuckle-joint 7, and tap-wire 8, having adjustable nuts or buttons 9, with the bellows 10, which is in communication with the wind-chest 11 by the passage 12. This 45 bellows is governed by a spring 13, which presses against the lever 14, pivoted at 15 to the post 16, its opposite end being connected in any suitable manner, as by a wire or rod 17, to the expression-pedal 18. A spring 19 50 is mounted on the lever 14 and connected to a block 20 or other suitable attachment.

21 shows a reed mounted in the wind-chest

covered by the pallet 22. The reed or reeds, however, may be replaced by an organ pipe or pipes, or both may be operated simultaneously.

The operation of my invention is as follows: The air from the feeder-reservoir or bellows enters the trunk usually at a constant pressure in the direction of the arrow. If now 60 the performer presses the pedal 18, the bellows 10 is compressed by the lever 14 and the valve 3 opened. Air from the trunk will now enter the wind-chest 11 until the pressure is sufficient to overcome the tension of the 65 spring 13, when the bellows 10 will raise or close the valve, thus diminishing or wholly cutting off the wind from the independent supply. As the pressure in the wind-chest falls, the bellows 10, acted upon by the spring 70 13, also falls, readmitting air to the chest and restoring the pressure.

The valve 3 may be varied to suit the particular construction of the instrument. For instance, it may be made V-shaped and pivoted, as at 23, so as to slide over a corresponding aperture 24 in the diaphragm. (See Figs. 2 and 4.) The spring 13 may also be replaced by a sliding weight or counterbalance 25, as in Fig. 2, which is adjustable.

In some cases I construct the valve as shown in Fig. 5, in which levers 26 26' are pivoted, as at 27, to the posts 28 28'. Wires 29 29' are fastened to the opposite ends of the levers and support two pallet-valves 3", closing apertures 24. One end of the lever 26' is connected to a spring 13', fastened to the base of the wind-chest. The other end is connected by a wire 31, passing through and attached to the flexible diaphragm 30, which 90 acts by internal pressure as a bellows and is attached by a second spring 32 to the governing-lever 14.

I claim—

1. In an organ the combination of the wind- 95 trunk, wind-chest and diaphragm separating them with a valve attached to the said diaphragm and controlling the flow of wind through the same, bellows supplied with wind from said wind-chest, a device connecting the 100 bellows with the valve, a spring controlling the said bellows and hand-operated means for varying the tension of said spring at will substantially as set forth.

2. In an organ the combination of the wind-trunk and wind-chest with the intervening diaphragm 2 provided with an aperture, the flanged valve 3 pivoted at 4 in the said aperture, the tap-wire 8 and bellows 10 operating the said valve, the spring 13 mounted on the bellows and controlling the same, the lever 14 resting on said spring, the spring 19 supporting the said lever and hand-operated 10 means for varying the tension of the spring

13 and the action of the bellows on the valve substantially as set forth.

In testimony that I claim the foregoing as my invention I have signed my name in presence of two subscribing witnesses.

JAMES RANDOLPH COURTENAY GALE.
